UNITED STATES PATENT OFFICE

WILLIAM A. ZEIDLER, OF NEW YORK, N. Y., ASSIGNOR, BY MESNE ASSIGNMENTS, TO
ALFRED B. KASTOR

SCISSORS

Application filed August 18, 1926. Serial No. 129,928.

This invention is directed to scissors and particularly to a type having removable cutting blades, that is, cutting elements which may be applied to, or removed from the main elements of the scissors and forming the cutting edges for the scissors.

The invention herein expressed is analogous to that defined in my co-pending application, Serial No. 60,745 filed October 6, 1925 issued as Patent No. 1,609,638, and dated December 7, 1926.

The invention in the present application, however, while effecting the desirable results defined in my co-pending application, has certain features of advantage not found therein.

The main object of the present invention is to provide a scissors having removable cutting blades, the various parts being so correlated that there is always perfect articulation between the cutting edges.

A further object is to so form and mount the cutting blades that they will be tensioned or stressed during the cutting operation in varying degrees, dependent upon the stress induced in the cutting operation.

These, and other objects more fully defined in the specification are enumerated in the claims.

Referring to the drawings:

Figure 1 is a plan view of a pair of scissors embodying the features of the invention.

Figure 2 is a fragmentary portion of one of the scissors elements showing the exterior side.

Figure 3 is a similar view of the element showing the interior side.

Figure 4 is a view of one of the removable cutting blades.

Figure 5 is a view looking directly at the point of the blade.

Figure 6 is an end view of the blade of Figure 4, looking from the right of said figure.

Figure 7 is a perspective view looking toward the cutting edge.

Figure 8 is a cross sectional view through the scissors on the line 8-8 of Figure 1.

Figure 9 is a similar cross section on the line 9-9 of Figure 1.

Figure 10 is a fragmentary view illustrating the method of removing blades.

Figure 11 is a plan view of the wrench employed for adjusting the scissors and removing the cutting blades.

In my co-pending application referred to, the blade was shown as having an impressed bend therein which gave it a normal offset from the holding element and served to snug and stress it upon said holding element when it was applied and anchored by the pintle.

Stressing was effected by a transverse angular engagement of the blade with the scissors element in order to provide always, perfect and true articulation of the cutting edges while they were functioning as cutters.

This particular feature in such a scissors is of paramount importance and it is maintained in the invention herein described in conjunction with additional features to provide a very efficient scissors of the removable blade type.

In place of utilizing a flat blade normally sprung away from its holding element and with a pocket at its end, the present invention contemplates forming a complete blade element hollow and providing a complete encasement of the element giving additional strength to the cutting blade and possibilities for fine grinding not heretofore possible.

In the accompanying drawings, numeral 1, denotes one of the scissors elements, and 2, the cooperating element. Both are provided with finger openings 3, 4, and the element 2, may have, as illustrated, a finger supporting hook 5.

Both elements have a pintle opening through which they are pivoted on a suitable pintle and each element, at its interior side, has a recess 6, for the reception of the end 7, of the cutting blade. Sunk below the bottom of the recess 6, is a depression 8, which extends beyond the wall of the recess 6, and a sufficient distance toward the pintle opening so that the end 7, of the blade will partially overlie the depression 8.

This depression 8, in conjunction with a suitable tool such as the wrench illustrated in Figure 11, forms a convenient means for ejecting the cutting blade from the element,

so that it may very readily be removed without liability of cutting or scoring the hands.

Naturally, the cutting blades will fit very accurately and snugly upon the scissors elements and the projecting "tang" 7, fits snugly within the recesses 6. Therefore it is difficult to pull the blades away from the holding elements unless they are first started and loosened as above described. This is readily accomplished, as is illustrated in Figure 10, where the end 9, of the wrench has been inserted in the depression 8, and turned against the rounded end of the blade to force it forward and outward from the recess 6.

15 This recess 6, for the end of the blade is comparatively long to aid in giving a lateral support for the cutting blade and in conjunction with the extended portion 10, of the element, gives a perfect support for the blade.

20 These elements 10, as best illustrated in Figure 9, are tapered from the back toward the meeting edges of the scissors and there is a distinct holding rib 11, extending along the upper and outer edge. This rib 11, extends 25 from the hub 12, to the outer end 13, and obviously lies in an angular position with reference to the inner edge 14.

This, in conjunction with the closely formed and fitted blade, provides a means for 30 tensioning the blade lengthwise during its cutting operation, much the same as the angular engagement of element and cutting blade in my co-pending application referred to.

35 In the present case, however, the action is even more delicate and the entire removable blade is backed up during its cutting operation by this engagement.

It will be noted both in Figs. 6, and 9, 40 that the blade has a main base portion 15, with the projecting tang 7, and at one side a cutting edge 16a.

The base portion continues into a rounded back 17, which is again folded over into a concave outer fold 18, the latter extending to the 45 cutting edge 16. The point of the shear blade is indicated at 21, and it will be noted that there is a curvature between the points X and Y, as indicated in Figures 6 and 7.

50 Of course, the edge 16, and the edge 16a and the folded over portion of the blade, are ground to give clearance from the actual cutting edge and the blade portion 15.

This removable blade is, of course, made 55 of a thin sheet stock capable of high tempering. As will be noted, it has formed therein, a distinct line of indenture 19, which provides, what is in effect a channel 20, extending along the blade and which exactly fits 60 over the rib 11. The rib and the channel 20, taper from the rear end toward the point of the blade. It follows that the blade is first of all backed up by the rear edge of the scissors element and is further backed up and 65 held to perfect alignment by the rib 11, which

occupies the position of an acute angle with a cutting edge.

With the blade anchored in the hub of the scissors any force applied to the cutting edge during a cutting operation tends to force the 70 blade against the rib 11, and there is, therefore, a tendency for stressing the blade with reference to the anchorage.

The result of this stressing tendency is to cause the edge of the blade to snug closely 75 into perfect articulation with the cooperating cutting blade. This gives a perfect cutting action without crushing, as of course, the blades are brought to what might be termed a razor edge. A further feature of construction is the blade itself, which aids in 80 its perfect articulation. As the elements 10, are moved toward each other in a cutting action, the main surfaces 15, of the blades, due to the anchorage of the blades, at the pivot, 85 and their extension within the recess 6, of the elements, are held to proper cutting alignment. As excessive pressure is exerted on the cutting edges, the upper portion of the blades 18, particularly at 19, ride against the 90 ribs of the element and thus cause the blades to snug into continued proper articulation at their edges. In other words, the cutting edges are "snugged" together as the blades ride 95 against the ribs of the elements, which ribs are at an acute angle to the cutting edges of the blades, there is a pronounced tendency for the blades to always pull toward each other at the cutting edges into perfect articulation 100 from end to end of the blades. If, on the other hand, the ribs 11, and channels 20, should lie parallel to the edges of the blades, the pressure and cutting action would tend to 105 separate the blades instead of inducing the pressure, which would cause the edges to snug against each other, in perfect articulation, as is the case in the present invention.

When the blades are formed, there is a very slight but perceptible twist or offset 110 thrown into the blade which is maintained to throw always, the cutting edges into true, following articulation.

This is again enhanced by the grinding which gives a perfect straight edge grind 115 to the cutting edge with a variance of a few thousandths between the point X, and the point Y, as indicated in Figure 7.

The concavity of the blade is maintained from end to end.

In this structure of blade a thin gauge 120 metal may be employed and when it is formed into the perfect envelope described, there is double thickness of metal for edge grinding. The closure at the edges is so perfect that the ground edge to all purposes and intents 125 is as though it were a homogeneous structure.

With the understanding that the end 7, is firmly anchored in the element and the co-operating rib 11, of the element and depression 19, of the blade hug tightly from end 130

to end, it would be apparent that during any cutting operation there is a tendency to stress the metal of the blades longitudinally. This throws the strain upon the blades which 5 causes their edges to come into closer articulation, dependent upon the stress imposed thereon.

It is this construction and action, so far as applicant is able to perceive, that gives 10 a perfect articulation and permits the formation of what is practically a razor edge for the cutting elements.

I have not specifically described the pintle employed and illustrated in Figure 8, as this 15 forms the subject of a copending application.

What I claim as my invention and desire to secure by Letters Patent is:

1. Scissors having elements for supporting removable scissors blades and with each element having a hub portion recessed to receive and support one end of the removable blade, and a depression extending under and beyond the blade, providing means for the insertion of a tool for ejecting the blade. 20

2. Scissors having elements for supporting removable scissors blades and each element having means for supporting one end of the blade and a depression in the element extending under and beyond the end of the blade, 25 providing means for the insertion of a tool for ejecting the blade.

3. Scissors having elements for supporting removable scissors blades and with each element having a perforation for a pintle, a 35 recess formed in the element about the pintle, and providing means for engaging its blade and a depression extending under and beyond the end of the blade and providing means for the insertion of a tool for ejecting the 40 blade.

4. Scissors having elements for supporting removable scissors blades, each element having a perforation for a pintle, means at opposite sides of the pintle and extending longitudinally of the element for preventing lateral movement of its blade, when the same is 45 engaged therewith, and a depression extending under and beyond the end of the blade providing means for the insertion of a tool for ejecting said blade.

5. Scissors having elements for supporting removable blades, each of said elements provided with a raised rib located at an angle to the cutting edge of the scissors, a removable 55 blade completely enveloping each scissors element and each blade having an interior longitudinal channel conforming to the rib of the element, each of said blades ground across its meeting edges to provide a cutting edge.

6. Scissors having elements for supporting removable blades, a removable blade fitting over and enveloping each of said elements and each having the meeting edges of the enveloping blade ground to a cutting edge, a 65 raised portion extending along each element

at an angle to the cutting edge of its blade and a corresponding formation in each enveloping blade to fit said rib.

7. A removable scissors blade comprising a formed up sheet metal element folded upon itself with its two edges brought closely together and ground away to a cutting edge, 70 said blade tapering from heel to point and a flat extension extending from the enveloping portion, providing means for attachment to a scissors element.

8. A removable scissors blade comprising a formed up sheet metal element folded upon itself with its two edges brought closely together and ground away to a cutting edge, 80 said blade tapering from heel to point and having interiorly thereof, at the side opposite the cutting edge, a channel and a flat extension extending from the enveloping portion, providing means for attachment to a scissors element. 85
